(No Model.)

J. BATLEY.

ELECTRIC MOTOR.

No. 388,753.

Patented Aug. 28, 1888.

UNITED STATES PATENT OFFICE.

JOHN BATLEY, OF PHILADELPHIA, PENNSYLVANIA.

ELECTRIC MOTOR.

SPECIFICATION forming part of Letters Patent No. 388,753, dated August 28, 1888.

Application filed June 29, 1887. Serial No. 242,849. (No model.)

To all whom it may concern:

Be it known that I, JOHN BATLEY, of the city and county of Philadelphia and State of Pennsylvania, have invented an Improvement 5 in Electric Motors, of which the following is a specification.

My invention has reference to electric motors; and it consists in certain improvements, all of which are fully set forth in the following 10 specification, and shown in the accompanying drawings, which form part thereof.

The object of my invention is to employ the direct attraction of the armatures of a series of electro-magnets to vibrate a series of levers, 15 which in turn cause a rotary movement of the motor-shaft. The construction embodied in my invention is simple and positive, and by a proper number of electro-magnet elements being employed I am enabled to make the motor 20 of any power desired. The magnets are arranged or coupled in two series, which are adapted to become energized alternately, and each of the electro-magnets is preferably supplied with electrical current from a separate 25 battery. By cutting out one or more of the batteries the corresponding electro-magnets are cut out, and hence the power of the motor may be correspondingly increased or decreased. An important feature of my 30 construction is that the operating-levers which act on the motor-shaft are caused to operate automatically, whether their operating-magnets are energized or not, so that all of the moving parts shall maintain a constant relation with each other and all danger to breakage due to irregular movements becomes 35 obviated.

In the drawings, Figure 1 is a side elevation of an electric motor embodying my improvements. Fig. 2 is a plan view of same showing the connection with the batteries. Fig. 3 is a perspective view showing the construction of the armatures, operating-levers, and friction-wheels; and Fig. 4 is a diagram showing the complete circuit between one battery 40 and one operating electro-magnet.

A is the frame of the machine.

B is the central stationary hub or frame, upon which the radiating electro-magnets C 45 and D are secured. These electro-magnets C and D are arranged in two series placed

side by side, and preferably staggered. The pole-pieces of these magnets are curved, though this is not an essential feature of the construction.

55

E is the motor-shaft, which is journaled in the frame A, and is provided upon each end with a circuit breaking and making commutator, F, and a friction-wheel, H. This friction-wheel is shown in elevation in Fig. 1 and in 60 perspective in Fig. 3, from which the construction may be clearly understood. It consists, essentially, of a notched wheel having the alternate projections I and notches J, the outer surface of the projections I being concentric with the shaft E, to which they are secured. The forward end of the projections I are provided with projections i, the purpose of which will be hereinafter explained.

65

L represents the armatures for the magnets C, and are pivoted at k, so as to vibrate to and from the pole, and for effect they are made curved to fit close to the said pole-piece of the magnet. These armatures vibrate a series of friction-levers, K, provided on their lower 70 parts with adjustable sections K', made adjustable by means of slots and clamping-screws k', and the lower portions of said parts K' are made curved from k as a center, and are adapted to press in contact with the projections I of 75 the wheels H, so as to form a rolling frictional contact. By the vibration of the armatures L it will be seen that the wheel H will be rotated a portion of a revolution, and then the friction-levers will return to their normal position ready for the next action, and so on, 80 returning in the spaces J without contact. To prevent the shaft E spinning or moving faster than it should with a given number of vibrations of the levers K, the stops or extensions i 85 are provided and are adapted to strike against pins M' on the lower part of the levers K, which pins are adapted to act as stops to arrest premature rotation. The rear ends of the levers K are provided with extensions h, which are 90 adapted to fit down at the rear of the projections I and insure a positive thrust to the wheel H at or about the termination of a semi-vibration.

95

From this it will be seen that the wheel H is estopped from running at a too high velocity, and while it is driven by frictional contact with the levers a positive thrust is also 100

insured with each vibration of the lever. The adjustment of the part K' allows the wear to be taken up and insures a good firm contact. As shown in the drawings, there are six sets 5 of magnets in each series, and consequently six levers K on each side; but I do not limit myself to any number, as one or more may be used. The levers on one side of the machine are thrown backward, while those upon the 10 other side of the machine are thrown forward, so as to keep up a constant forward motion of the shaft E. To enable the proper action of these levers when so arranged, the wheels H are so set that the projections I on the two 15 wheels are staggered. (See Fig. 3.)

M represents the armatures for the D series of electro-magnets, and are pivoted at m and secured to the other series of levers K. (See Fig. 3.) The armatures M and L are connected 20 together by means of an arm, L, extending rearwardly from the armature M, and having a slot, m, and into which extends a pin, l, secured to the free end of the armature L. From this it will be seen that as the armature L is 25 attracted to its magnet the armature M is raised, and vice versa, and in this connection it will also be observed that the backward movement of the levers K are caused by the attraction of the magnets in the other series to 30 which they belong, thereby avoiding all the necessity of springs or counter-balances, and also the employment of but a minimum number of electro-magnetic elements.

G represents the commutator-brushes, which 35 are arranged in pairs, so that the current passes down one brush through the commutator and back through the other brush. One of these brushes of each pair leads to its battery R and the other brush leads to one of the electro- 40 magnets of the motor, and the current returns to the battery by a circuit having a switch, S. This is clearly shown in Fig. 4, and is simply duplicated in the plan view, Fig. 2. Each electro-magnet of the two series is provided 45 with its own complete circuit Q, and its own battery and its own switch S to open the circuit Q. As the commutator F rotates, the magnets of the two series are alternately energized, and thereby keep up a continuous action 50 upon the motor-shaft.

If desired, one or more of the magnets C and D may be simultaneously cut out of action by means of the switches S; but from the nature of the construction of the friction-levers and friction-wheels the armature and levers will continue to work even though their 55 particular magnets are not energized.

While I prefer the construction shown I do not limit myself to the details thereof, as they 60 may be modified in various ways without departing from my invention.

Having now described my invention, what I claim as new, and desire to secure by Letters Patent, is—

65 1. The combination of a series of electro-magnets arranged in a circle, a motor-shaft, a

friction-wheel secured to the motor-shaft, a series of friction-levers operating on the friction-wheel, and a series of armatures to actuate said friction-levers.

70

2. The combination of a series of electro-magnets arranged in a circle, a motor-shaft, a friction-wheel secured to the motor-shaft, a series of friction-levers operating on the friction-wheel, and a series of armatures to actuate said friction-levers, a source of electric energy, separate circuits for each of said magnets, and suitable switches to cut out of circuit one or more of said electro-magnets.

75

3. The combination of a series of electro-magnets arranged in a circle, a motor-shaft, a friction-wheel secured to the motor-shaft, a series of friction-levers operating on the friction-wheel, a series of armatures to actuate said friction-levers, a separate battery to each magnet, 85 circuits connecting each battery with its electro-magnet, a commutator to throw said magnets into or out of circuit, and separate switches to cut out one or more of said batteries.

80

4. The combination of a series of electro-magnets arranged in a circle, a motor-shaft, a friction-wheel secured to the motor-shaft, a series of friction-levers operating on the friction-wheel, a series of armatures to actuate said friction-levers, a source of electric energy, separate circuits for each of said magnets, suitable 95 switches to cut out of circuit one or more of said electro-magnets, and a commutator to put said magnets into or out of circuit.

90

5. The combination of two series of electro-magnets arranged in circles, a motor-shaft having two friction-wheels, two sets of armatures, one for each set of magnets, friction-levers actuated thereby and operating in connection with the friction-wheels to rotate the 105 shaft, a source of electric energy, separate circuits for each series of electro-magnets, and commutators to alternately put each of said series of electro-magnets into and out of circuit.

100

6. The combination of two series of electro-magnets arranged in circles, a motor-shaft having two friction-wheels, two sets of armatures, one for each set of magnets, connections between the armatures of the two series, so 115 that when one is attracted the other is raised, friction-levers actuated thereby and operating in connection with the friction-wheels to rotate the shaft, a source of electric energy, separate 120 circuits for each series of electro-magnets, and commutators to alternately put each of said series of electro-magnets into and out of circuit.

110

7. The combination of two series of electro-magnets arranged in circles, a motor-shaft 125 having two friction-wheels, two sets of armatures, one for each set of magnets, friction-levers actuated thereby and operating in connection with the friction-wheels to rotate the shaft, a source of electric energy, separate 130 circuits for each series of electro-magnets, commutators to alternately put each of said

- series of electro-magnets into and out of circuit, and switches to cut out of circuit one or more of the electro-magnets of each series.
8. The combination of a series of electro-magnets arranged in a circle, a motor-shaft, a friction-wheel secured to the motor-shaft, a series of friction-levers operating on the friction-wheel, a series of armatures to actuate said friction-levers, a source of electric energy, 5 separate circuits for each of said magnets, suitable switches to cut out of circuit one or more of said electro-magnets, and means, substantially as set forth, to actuate said friction-levers when their operating electro-magnets 10 are cut out of circuit.
9. The combination of two series of electro-magnets arranged in circles, a motor-shaft having two friction-wheels, two sets of armatures, one for each set of magnets, friction-levers actuated thereby and operating in connection with the friction-wheels to rotate the shaft, a source of electric energy, separate 15 circuits for each series of electro-magnets, commutators to alternately put each of said 20 series of electro-magnets into and out of circuit, and means, substantially as set forth, to actuate said friction-levers when their operating electro-magnets 25 are cut out of circuit.
10. The combination of two series of electro-magnets arranged in circles, a motor-shaft having two friction-wheels, two sets of armatures, one for each set of magnets, connections between the armatures of the two series, so that when one is attracted the other is raised, 30 friction-levers actuated thereby and operating in connection with the friction-wheels to rotate the shaft, a source of electric energy, separate 35 circuits for each series of electro-magnets, commutators to alternately put each of said series 40 of electro-magnets into and out of circuit, switches to cut out of circuit one or more of the electro-magnets of each series, and means, substantially as set forth, to actuate said friction-levers when their operating electro-magnets 45 are cut out of circuit.
11. The combination of a motor-shaft, a notched friction-wheel secured thereto and electro-magnets, a pivoted armature therefor, and a pivoted friction-lever actuated thereby and 50 having its operating-face curved to work in contact with the raised portions of the friction-wheel.
12. The combination of a motor-shaft, a notched friction-wheel secured thereto, an electro-magnet, a pivoted armature therefor, a pivoted friction-lever actuated thereby and having its operating-face curved to work in contact with the raised portions of the friction-wheel, and stops, substantially as set forth, to 55 prevent the friction-wheel revolving faster than required by the vibrations of the friction-lever.
13. The combination of a series of electro-magnets arranged in a circle, a motor-shaft, a notched friction-wheel secured to the motor-shaft, a series of levers to act upon said friction-wheel by rolling contact and having projections which work in the notches of the friction-wheel to positively thrust it at the last portion of the vibration of said levers, and a 60 series of armatures to vibrate said friction-levers.
14. The combination of a series of electro-magnets arranged in a circle, a motor-shaft, a notched friction-wheel secured to the motor-shaft, a series of levers to act upon said friction-wheel by rolling contact, and having projections which work in the notches of the friction-wheel to positively thrust it at the last portion of the vibration of said levers, and a 65 series of armatures to vibrate said friction-levers, and adjusting devices to adjust the contact portion of the friction-levers to or from the friction-roller.
15. The combination of a series of electro-magnets arranged in a circle, a motor-shaft, a friction-wheel secured to the motor-shaft, a series of friction-levers operating on the friction-wheel, a series of armatures to actuate said friction-levers, and adjusting devices to 70 adjust the contact-surface of the friction-levers to or from the friction-wheel.
16. In an electromotor, the combination of a series of stationary actuating electro-magnets, a series of pivoted vibrating armatures, 75 a separate source of electrical energy to each of said magnets, and switches to cut out one or more of said electro-magnets from its source of energy.
17. In an electromotor, the combination of two series of actuating electro-magnets, a series of pivoted vibrating armatures therefor, a separate source of electrical energy to each electro-magnet, and switches for simultaneously cutting out of circuit one or more corresponding electro-magnets from each series. 80
18. In an electromotor, the combination of a series of radially-arranged actuating electro-magnets, a separate source of electrical energy for each of said magnets, a motor-shaft, 85 a circuit-breaker on said shaft, and separate circuits controlled by said circuit-breaker to simultaneously make or break all of the circuits, so that all of the magnets are simultaneously energized or demagnetized.
- In testimony of which invention I hereunto set my hand.

JOHN BATLEY.
